DEODORIZING DEVICE

Application filed July 27, 1931. Serial No. 553,450.

This invention relates to a novel improvement in disinfecting and deodorizing device for toilets, toilet bowls, and the like.

An object of our invention is to provide an article which is simple in construction, inexpensive to manufacture, and which can be quickly and easily mounted in a position to be more effective.

Another object is to provide a novel disinfecting and deodorizing device which can be readily mounted in the water openings under the rim of the bowl, or can be attached to the rim of the bowl in such a manner that it can be easily removed when the active materials are exhausted.

Other objects, advantages, and features of invention may appear from the accompanying drawing, the subjoined detailed description, and the appended claims.

20 In the drawing

Figure 1 is a fragmentary, transverse, sectional view of a bowl with our deodorizing device placed therein.

25 Figure 2 is a side elevation of one form of deodorizing device.

Figure 3 is a fragmentary, transverse, sectional view of a bowl illustrating a slightly modified form of mounting our deodorizing device thereon.

30 Figure 4 is a side elevation of the form of device shown in Figure 3.

Referring more particularly to the drawing, the numeral 1 indicates a toilet bowl in the rim 2 of which a plurality of water holes 3 are provided. Our deodorizing device 4 consists of a substantially cylindrical block of a suitable deodorizing and disinfecting material 5. This block is composed of certain active ingredients which either dissolve in the water or gradually evaporate, or both.

A piece of wire 6 extends axially of the cylinder 5 and said cylinder is molded on to this wire during the course of manufacture. 45 A loop 7 is formed in the wire adjacent the end of the cylinder 5 and from this loop the wire is bent into a curved section 8 which extends into one of the holes 3 to mount the cylinder 5 under the rim of the bowl as shown 50 in Figure 1. The loop 7 imparts a tension

or a downward pull to the section 8 so that the cylinder 5 is held securely in position.

In Figures 3 and 4 we have shown a slightly modified form of mounting the block of disinfecting material, which form is substantially as follows: A block of disinfecting material 9, substantially cylindrical in form, is molded around a wire 10 which extends axially thru said block. The wire 10 is bent into an angular hook 11 which is adapted to fit over the rim 2 of the bowl substantially as shown in Figure 3. The hook 11 is sprung over the rim of the bowl and the spring action of the wire is sufficient to hold the cylinder 9 tightly against the inner edge of the bowl and under the rim substantially as shown in Figure 3. The block or cylinder 9 is formed of disinfecting and deodorizing materials of the same character as previously described for the type shown in Figures 1 and 2.

While we have illustrated our disinfecting material mounted upon, or in a toilet bowl, it is obvious that the disinfecting block could be mounted adjacent to the bowl or in any other place found advisable.

Having described our invention, we claim:

1. In a deodorizing device for mounting upon a toilet bowl, a resilient wire bent upon itself to form a pair of clamping legs extending in substantially the same direction, substantially parallel and resiliently urged toward each other, and a block of solid deodorant mounted upon one of said legs, the other of said legs being curved for insertion into a water opening in said bowl to clamp said deodorant to the surface of said bowl.

2. In a deodorizing device for mounting upon a toilet bowl having a perforated interior rim for water entrance to said bowl, a resilient wire bent upon itself to form a pair of clamping legs extending in substantially the same direction, substantially parallel and resiliently urged toward each other, one of said legs being adapted for insertion in said water openings, and a block of solid deodorant mounted upon the other of said legs and held in clamping relation to the rim of said bowl immediately below said water openings.

3. In a deodorizing device for mounting

upon a toilet fixture, a resilient wire bent upon itself to form a loop and a pair of clamping legs resiliently urged toward each other, and a block of solid deodorant material mounted upon one of said legs, the other 5 of said legs adapted to extend substantially parallel to said first-named leg and arranged to bear against a portion of said toilet fixture to clamp said deodorant to the surface of said fixture.

10 In testimony whereof, we affix our signatures.

CHARLES D. HOLMES.
HARVEY W. GAMEL.
